BOTTLE CAP

John F. Price, Fulton, N. Y., assignor to Oswego Falls Corporation, Fulton, N. Y., a corporation of New York

Application February 23, 1937, Serial No. 126,959

4 Claims. (Cl. 215—38)

This invention relates to bottle caps for milk bottles and the like, and more particularly to caps formed of fibrous material such as paper or paper-board, and of the type embodying an outwardly flaring flange extending over the top edge or pouring lip of the bottle.

These caps are formed from a blank of sheet material and comprise a central discoidal portion having an upwardly extending peripheral flange arranged to be pressed in the mouth of the bottle, 10 and which flange extends outwardly over the bead of the bottle and downwardly a short distance about the periphery of the bead. In order that these caps may be tightly retained in operative 15 position during handling of the filled bottle, a disk of relatively thick fibrous material is arranged within the upstanding peripheral flange and acts as a backing therefor to press the same radially outwardly and maintain the same against 20 the bore of the bottle mouth.

The body of the cap is usually formed by drawing the blank with punch and die mechanism, and the thick backing disk is subsequently inserted in the flange of the cap and the cap is 25 shipped to the user in this manner. The backing disk resembles the conventional plug disk milk bottle cap, and on which is applied suitable printing designating the contents of the bottle and the name of the dairy.

When the backing disks are pressed into the flanges under pressure sufficient to retain them in the flange until the cap is applied to the bottle, such initial strain or stress on the flange of the cap often results in the caps warping, because 30 of climatic or atmospheric changes, to an extent where the caps are unfit for use.

If the backing disk is of such diameter as to loosely fit into the flange of the body, difficulty is encountered during the manufacture of the 40 cap in that the backing disk is fed over the formed body and positioned in the aperture through which the punch travels for initially forming the body. In order that the backing disk will loosely fit the flange, it must be of slightly 45 less diameter than the forming plunger or punch, and this results in the backing disk dropping of its own volition into the flange, and often it does not drop in a plane parallel with the discoidal portion of the body. That is, the disk does not 50 drop into proper seating position, with the result that the cap is not properly formed and the cap forming machine becomes disorganized. Also, if the backing disk is loosely seated in the flange of the body, there is a great possibility of the back- 55 ing disk falling out of the flange during shipment

and handling of the cap previous to its application to the milk bottle.

An object of this invention is to provide a milk bottle cap of the type referred to of such construction that the backing disk is maintained in 5 the flange of the cap without exerting any appreciable radial pressure on the flange, and at the same time when the cap is applied to the bottle, the periphery of the backing disk presses the flange tightly against the bore of the bottle 10 mouth.

The invention consists in the novel features and in the combinations and constructions hereinafter set forth and claimed.

In describing this invention, reference is had 15 to the accompanying drawing in which like characters designate corresponding parts in all the views.

Figure 1 is a top plan view of a cap embodying 20 my invention and being applied to a bottle with a portion of the cap and bottle in section.

Figure 2 is a view taken on lines 2—2, Figure 1.

Figure 3 is a side elevational view of the cap shown in Figures 1 and 2 with certain parts broken away and other parts shown in section. 25

The body of the cap here shown comprises a central discoidal portion 10 formed with an up-standing peripheral flange 11 which merges with an outwardly flaring flange, here shown as comprising a plurality of angular surfaces 12 joined 30 by an intermediate horizontally arranged section 13 and terminating in a vertical wall 15 encircling the periphery of the bottle bead.

The flange 11 is formed with its external diameter slightly greater than the internal diameter of 35 the bore 16 of the mouth of the bottle B. As here shown, the external surface of the flange 11 is formed with a plurality of circumferentially spaced apart, axially extending ribs or recesses 18 to permit the escape of milk, when the cap is 40 applied to an overfilled bottle.

It is necessary that caps of this type be secured 45 to the bottle in a firm manner, due to the fact that the milk bottles are usually handled by grasping them by the bead at the top of the bottle, and inasmuch as this type of cap covers the pouring lip or upper portion of the bead, it is necessary that these caps be applied to the bottle in such a manner that they will support the weight of the filled bottle. This result is accomplished by arranging a backing disk 20 of comparatively stiff material in the flange 11, and in these caps as now manufactured, the relative dimensions of the backing disk 20, flange 11 and the bore 16 in the bottle mouth are such that con- 50 55 55

siderable pressure is applied to the cap in forcing it into the mouth of the bottle. That is, the external diameter of the flange 11 is slightly greater than the bore of the bottle mouth, and when it is moved axially therein it is prevented from springing radially inwardly by the backing disk 20.

This invention has to do particularly with means for maintaining the backing disk 20 in the flange 11 during shipment and handling of the caps previous to their application to the bottle, and at the same time not creating any undue stress on the flange 11 which would result, by change of atmospheric conditions, in warping of the cap.

It will be understood by those familiar with the paper conversion art that paper products will, during changes in atmospheric conditions, shrink or contract, and the direction of this contraction depends upon the grain of the paper. Where an article comprises two or more separate paper elements, the grain of the paper in the respective elements may be such relatively as to effect considerable warping of the article. In caps of the type referred to now in use, the backing disk 20 is pressed into the flange 11 with the periphery of the disk in tight engagement with the flange, and there is accordingly no possibility of relative contraction or expansion of these elements with the result that when such action takes place, the cap curls up or warps to the extent where it is not fit for application to a bottle.

In my invention, this trouble is overcome by forming the backing disk 20 of slightly less diameter than the internal diameter of the flange, and employing means for maintaining the disk in the flange previous to the application of the cap to the bottle. In the embodiment here shown, this result is accomplished by forming the inner surface of the flange 11 with a plurality of circumferentially spaced apart upwardly extending ribs 21.

The disk 20 is formed of a diameter slightly less than the internal diameter of the flange 11 and somewhat greater than the diametrical distance between the surfaces of the ribs 21. Accordingly, during the manufacture of the cap, as the backing disk 20 is pressed into the flange 11, the periphery of the disk 20 engages the ribs 21. The ribs 21 are slightly resilient, and the backing disk 20 is accordingly retained in the flange 11 by engagement with the ribs 21, there being a slight clearance between the flange 11 and the periphery of the disk 20 intermediate the ribs 21, as indicated to the right, Figure 3.

When the cap is subsequently applied to the bottle, the flange 11 is pressed into the bore 16 of the bottle, and after it has been forced slightly inwardly, it engages the periphery of the backing disk 20, see Figures 1 and 2, and is prevented from further inward movement, with the result that it is pressed snugly into the bore of the bottle mouth, and the cap is retained on the bottle during handling of the filled bottle. Previous to

the application of the cap to the bottle any contraction of the body of the cap, due to changes in atmospheric conditions, is permitted through the resiliency of the ribs 21.

The ribs 21, and in the embodiment shown the recesses 18, are formed by the punch and die drawing mechanism. That is, they are produced simultaneously during the formation of the body of the cap. This results in obtaining the advantages of the invention without any additional cost in the manufacture of the cap.

What I claim is:

1. A milk bottle cap comprising a discoidal portion formed with an upstanding peripheral flange, the inner surface of said flange being formed with a plurality of circumferentially spaced apart ribs extending upwardly from said discoidal portion, and a disk of relatively stiff material arranged in said flange with the periphery of the disk in engagement with said ribs. 20

2. A milk bottle cap comprising a discoidal portion formed with an upstanding peripheral flange, a backing disk of relatively stiff material arranged on said discoidal portion within said flange, the inner surface of said flange being formed with a plurality of circumferentially spaced apart ribs extending upwardly from said discoidal portion, said disk being of slightly less diameter than the internal diameter of said flange and having its periphery in engagement with said ribs to retain said disk within said flange previous to the application of the cap to the bottle, said ribs being resilient to permit said flange to move radially inward to engage the periphery of said disk when said cap is applied to 35 the bottle.

3. The combination of a bottle and a closure unit therefor, said closure unit comprising a discoidal portion formed with an upstanding peripheral flange, a disk of relatively stiff material arranged in said flange on said discoidal portion, the external diameter of said flange being slightly greater than the internal diameter of the bottle mouth, said disk being of lesser diameter than the internal diameter of said flange, the internal 45 surface of said flange being provided with means coacting at circumferentially spaced apart points with the peripheral edge of said disk to retain the same in the flange before application of the closure unit to the bottle, and said means being 50 yieldable to permit engagement of said flange with the edge of said disk when the closure unit is applied to the bottle mouth.

4. A milk bottle cap comprising a discoidal portion formed with an upstanding peripheral 55 flange, the inner surface of said flange being formed with a plurality of circumferentially spaced apart ribs extending upwardly from said discoidal portion, and a disk of relatively stiff material arranged in said flange with the peripheral edge of the disk in engagement with said ribs. 60
